CLOSURE PLUG AND METHOD OF
FORMING SAME

John P. Jesevich, Chicago, Ill., assignor to American Flange & Manufacturing Co., Inc., a corporation of Illinois

Application March 11, 1932, Serial No. 593,111

12 Claims. (Cl. 29—148.2)

My invention relates to closure plugs and method of forming same; and has to do particularly with a plug well adapted for closure of the openings in metallic containers suited for transportation and storage of oil, gasoline, and the like.

One of the objects of my invention is to provide an improved, simple and inexpensive, yet highly efficient and durable, closure plug formed of sheet metal.

10 A further object is to provide a light weight plug of the foregoing character which has an externally threaded, cup-shaped body, an exterior gasket-receiving and supporting surface, a head with a seal seat thereon and means within the body and interlocked therewith in the formation of the plug for facilitating insertion and removal of the plug from the opening which is adapted to close.

20 An additional object is to provide a novel and inexpensive method of forming the plug, the same being carried out in such a manner as to thicken the material and strengthen the completed structure sufficiently to withstand all conditions of use, notwithstanding the final threading and finishing operations thereof.

Other objects and advantages will become apparent as this description progresses and by reference to the drawing wherein,—

25 Figure 1 is a perspective view of a blank from which the body of the plug may be formed;

Fig. 2 is a vertical sectional view of die structure (somewhat diagrammatically shown) for initially forming the blank of Fig. 1 into a cup shape;

30 Fig. 3 is a perspective view of the cup formed by the die of Fig. 2;

Fig. 4 is a perspective view of a pre-formed insert adapted to be set into the cup of Fig. 3;

35 Fig. 5 is a top plan view of the cup of Fig. 3 showing the insert of Fig. 4 therein;

Fig. 6 is a section taken substantially on line 40 6—6 of Fig. 5;

Fig. 7 is a section taken substantially on line 45 1—7 of Fig. 5;

Fig. 8 is a vertical sectional view of die structure (somewhat diagrammatically shown) for compressing and interlocking the structure of Figs. 5 to 7 inclusive;

50 Fig. 9 is a horizontal section through the structure formed by the die of Fig. 8, which view is taken substantially on line 9—9 of Fig. 8; and

Fig. 10 is an elevational view partially in section, of the finished plug.

Generally speaking, in making a plug in accordance with my invention I take a pre-formed cy-

lindrical blank of sheet metal of desired size and form it into a cup, the side walls of which taper slightly outward. I next take a substantially rectangularly shaped blank of sheet metal and double the same along its longitudinal median line and seat this pre-formed blank diametrically within the initially formed cup. This assembled structure is then acted upon by a die in such a manner that the side wall of the cup is compressed in axial direction, thereby thickening the cup side 10 wall and, at the same time, causing the metal of the side wall to flow around and encompass the ends of the blank inserted within the cup, securely embedding the ends of this insert within the side wall of the cup and making it substantially 15 an integral part of the formed structure. The foregoing operation gives the structure its desired height and the plug is finally completed by externally threading the foregoing structure and by shaping the upper exterior part of the structure above the threads to provide a gasket receiving space and a head having a seal seat surface.

In the drawing I have illustrated the foregoing steps of my invention together with one form 25 of structure which may be employed therefor. Specifically, with respect to the drawing, the pre-formed cylindrical sheet metal blank 15 is shaped into the form of a cup 16 (Figs. 2 and 3) by male and female die members of any suitable 30 and well-known form such as illustrated at 17 and 18, respectively. The die members 17 and 18 are so shaped that the side wall of the cup 16 flares outwardly to a slight extent (see Fig. 7), and within this cup I insert a cross member 19. 35 This cross member is formed from a flat, rectangularly shaped piece of sheet metal, doubled upon itself, as illustrated in Fig. 4, to provide a member of inverted U-shape in cross-section with its U-legs 19^a and 19^b spaced slightly apart. 40 As will be noted in Fig. 6, the member 19 is of such length that it seats against the inner wall of the cup 16 at a point spaced slightly from the bottom of the cup; however, as will be seen hereinafter, in the final forming operation, this member 19 is lowered with its bottom edge substantially seated on the bottom of the cup.

After the member 19 has been properly inserted in its diametrical position within the cup 16, this assembled structure is seated within the female die member 20 of the composite die structure 21 (Fig. 8). The die member 22 is then moved downwardly in any desired manner in engagement with the side wall of the initially formed cup 16 compressing the cup side wall to 55

the height or cup depth, approximately, as illustrated in Fig. 8. An inner die member 23 having a central space 24 receives, guides and supports the insert 19 during the foregoing forming operation. Upon the completion of this operation, the cup side wall is compressed to substantially the height of the insert 19 so that the upper surfaces of these parts are, preferably, substantially flush with each other. However, it is obvious that the height dimensions of the insert member 19 may vary so as to project above or below the upper rim of the cup, without departing from my invention.

As the side wall of the cup 16 is compressed to form the cup 16' (Figs. 8 and 9) the metal of its side wall is thickened by flowing of the same laterally within the space between the die members 20 and 23. In this operation the cup side wall metal is caused to flow around the ends of 20 and between the U-legs 19^a, 19^b of the member 19, thereby embedding and fixing this member firmly, securely and non-removably therein. This action is so effective that the insert member 19 and the cup become, in effect, integral parts; 25 wherefore, the plug structure is additionally braced and strengthened, and a strong and efficient means is provided within the plug for engagement with a suitable tool, such as the jaws of a monkey-wrench, for screwing the plug into 30 and out of the opening which it is to close, and this advantage is gained by an arrangement which does not add materially to the weight of the plug.

After the structure is preformed to the extent stated, its lower exterior portion is threaded in any desired manner as at 25, and its upper exterior portion is cut away on an angle at 26 providing a seat seal surface and defining a plug head 27. The threads 25 terminate at a point somewhat below the angled head surface 26 leaving a plane annular surface 28 which is adapted to receive a seal gasket of any suitable character.

The advantages of my invention first above stated will be obvious from the foregoing. A 45 simple and inexpensive plug formed of sheet metal is provided for. The plug is of light weight, which is a material factor with respect to shipping expense; and it is of sufficient strength to withstand all conditions of use. For 50 example, among other things, a flat bar of metal may be substituted for the U-section cross piece 19 with good results.

I claim:

1. A closure plug formed entirely of sheet metal comprising a cup-shaped body, having a bottom and a relatively thicker and compacted side wall, the lower exterior portion of said body being threaded and the upper exterior portion adjacent the top of said body being cut away on an angle providing an upwardly and outwardly tapering seat and defining a head, said seat surface being spaced from the top of said threaded portion by an annular gasket-receiving surface.

2. The method of forming a sheet metal closure plug having a cup-shaped body with its interior spanned by a member, which comprises shaping a preformed cylindrical blank into cup form, placing a preformed sheet metal piece in the cup spanning the interior thereof, and compressing the side wall of the cup to thicken the cup side wall and to simultaneously interlock the opposite ends of said sheet metal piece therewith.

3. The method of forming a closure plug of

the class described which comprises shaping a preformed blank of sheet metal to cup form, inserting a sheet metal piece crosswise of and within the cup, and compressing the side wall of said cup uniformly to cause the metal thereof to flow around the ends of said cross piece and fix the latter thereto in a projection-less manner.

4. The method of forming a closure plug of the class described which comprises shaping a preformed blank of sheet metal to a cup form having a side wall of substantially uniform thickness throughout and of greater height than the height of the finished plug, and compressing the side wall of said cup in axial direction to the height of the finished plug and uniformly thickening the side wall thereof, and finally shaping the exterior of said side wall to form a threaded surface with a head at the top.

5. The method of forming a closure plug of the class described which comprises shaping a preformed blank of sheet metal to a cup form having a side wall of uniform thickness and of greater height than the height of the finished plug, compressing the side wall of said cup in axial direction to the height of the finished plug and uniformly thickening the side wall thereof, and then threading the lower outer wall of said cup.

6. The method of forming a closure plug of the class described which comprises shaping a preformed blank of sheet metal to a cup form having a side wall of greater height than the height of the finished plug, compressing the side wall of said cup in axial direction to the height of the finished plug and thickening the side wall thereof, then threading the lower outer wall of said cup and cutting away the upper exterior portion of the cup at an angle to form an angular seat surface and to define a head.

7. The method of forming a closure plug of the class described which comprises shaping a preformed blank of sheet metal to cup form, inserting a sheet metal piece preformed to shape having inverted U-shape in cross-section within the cup, and compressing the side wall of the cup in axial direction to cause the metal thereof to flow around the ends of the inserted piece and between the U-legs thereof.

8. The method of forming an all-sheet-metal closure plug which comprises the steps of preforming a piece of metal to cylindrical blank form, giving said blank a cup shape, inserting a preformed piece of sheet metal within the cup, and compressing the side wall of the cup in axial direction to reduce it to substantially the height of the finished plug and to simultaneously interlock the ends of the inserted piece with the inner wall of the cup.

9. An article of the class described comprising a sheet metal and cup-shaped externally-threaded body having a head formed at the upper edge of its outer side wall, and a continuous and unobstructed seal-seat surface between said head and threaded body and parallel to the axis of the article, and a cross member within said body and having its ends rigidly embedded within the material forming the inner wall of said body.

10. A closure plug formed entirely of sheet metal comprising a single-piece cup-shaped body, a head on said body, a continuous annular seal seat formed exteriorly on the under side of said head and with its surface parallel to the axis of the plug, and a member spanning the interior of said body and having its ends secured to the inner wall of said body by forming the inner wall of the latter uniformly therearound.

11. A closure plug formed entirely of sheet metal comprising a cup-shaped body having a bottom and a relatively thicker and more compacted side wall, and a sheet metal member mounted within said body and of a width substantially equal to the depth of said body and of a length adapted to span the interior of said body, the opposite ends of said member being embedded in the inner side wall of said body.

12. A closure plug formed entirely of sheet metal comprising a cup-shaped body, and a member of inverted U-shaped cross-section mounted within said body and spanning the interior thereof, said member extending substantially from the bottom to the top of said body and having its opposite ends fixed to said body by embedding the same in the side wall of the body.

JOHN P. JESEVICH.
